DESIGN FOR A COMBINED KNIFE AND COMB FOR FUR CUTTERS

Thomas Albert Bernier, Fargo, N. Dak.

Application March 26, 1935, Serial No. 56,063

Term of patent 14 years

To all whom it may concern:

Be it known that I, Thomas Albert Bernier, a citizen of the United States, residing at Fargo, in the county of Cass and State of North Dakota, have invented a new, original, and ornamental Design for a Combined Knife and Comb for Fur Cutters, of which the following is a specification, reference being had to the accompanying drawing, forming part thereof.

Figure 1 is a view in elevation of the combined knife and comb showing my new design;

Figure 2 is a cross section taken on the line 2—2 of Figure 1.

I claim:

The ornamental design for a combined knife and comb for fur cutters, as shown.

THOMAS ALBERT BERNIER.
